Attorney

UNITED STATES PATENT OFFICE.

JOHN R. WATTS, OF CHICAGO, ILLINOIS.

OIL BURNER.

Application filed January 15, 1923. Serial No. 612,660.

To all whom it may concern:

Be it known that I, JOHN R. WATTS, citizen of the United States, residing at Chicago, in the county of Cook and State of Illinois, have invented certain new and useful Improvements in an Oil Burner; and I do hereby declare the following to be a full, clear, and exact description of the invention, such as will enable others skilled in the art 10 to which it appertains to make and use the same.

My invention relates to oil burners of the general class employed for heating boilers or the like, and in its general objects aims to 15 provide a simple, inexpensive, durable, easily adjusted and highly efficient burner for such purposes.

In some of its more particular aspects, my invention aims to provide a burner which 20 will duly preheat both the air and the oil and which will be particularly effective as to preheating of the oil so as to deliver the latter in an approximately vaporized state into the mixing chamber in which it is inter- 25 mingled with the steam employed for projecting the oil through the nozzle of the burner. My invention also aims to provide means associated with the nozzle for widening the spray of the combustible mixture 30 after this leaves the nozzle and thereby concentrating the spray near the nozzle instead of permitting the pressure to project the spray for an undesirably long distance. For this latter purpose, my invention aims to 35 provide movable means actuated by the flow of the emitted mixture and desirably aims to provide such movable means in the form of a vane mounted axially of the nozzle and forwardly of the mouth of the nozzle proper.

Moreover, my invention aims to provide a fuel burner construction which will readily permit the constituent elements to be taken apart for inspection or for a possible replacement, and which will readily permit 45 desired adjustments to be made for controlling the density of the spray and the amount of air supplied to the burner. Still further and also more detailed objects will appear from the following specification and from 50 the accompanying drawings, in which—

Fig. 1 is a side elevation of an oil burner

embodimenting my invention, with a portion of the outer casing broken away to show the air space between this and the inner casing or steam chamber.

Fig. 2 is a side elevation of the same burner with the outer casing removed and with a portion of the inner casing cut away to show the coiled portion of the oil tube.

Fig. 3 is a side elevation showing the entire oil tube of the burner withdrawn from the said inner casing.

Fig. 4 is a side elevation of the straight or axial portion of the oil tube and of the nozzle carried by the same.

Fig. 5 is an enlarged end view of the same oil burner, taken from the left-hand end of Fig. 1.

Fig. 6 is a correspondingly enlarged longitudinal section through the burner taken 70 along the line 6—6 of Fig. 5.

Fig. 7 is a correspondingly enlarged transverse section through the nozzle, taken along the line 7—7 of Fig. 1.

Fig. 8 is a correspondingly enlarged 75 transverse section taken through the burner along the line 8—8 of Fig. 1.

Fig. 9 is a correspondingly enlarged transverse section taken along the line 9—9 of Fig. 1.

In accomplishing the purposes of my invention after the manner of the illustrated embodiment, I provide a pipe 1 which forms an outer casing freely housing an inner casing 2. This inner casing or steam chamber is also desirably in the form of a pipe projecting at both ends beyond the outer casing 1, and is held in position within the outer casing by two groups of set screws 3 and 4, which set screws not only prevent the inner casing from shifting lengthwise with respect to the outer casing but also maintain the two casings coaxial so as to provide a suitable air space 5 between the two.

Threaded on the rear end of the inner 95 casing 2 is an elbow casting 6 which is connected at its bottom to a steam supply pipe 7 and which also is connected at its rear end to an oil supply pipe 8. This oil supply pipe leads to a bore 9 extending coaxial with the nozzle (or in alignment with the common axis of the two casings 1 and 2) and leads

to a straight oil duct 10 threadedly connected to the elbow 6 and extending axially of the casings towards the nozzle of the burner. This straight oil duct 10 is housed for a considerable portion of its length by a return oil pipe 11 having a bore somewhat larger than the outside diameter of the duct 10 so as to leave a clear space all around the latter. The return pipe 10 is threaded at its forward end into the rear end 12 carried by the core 13 of the nozzle, the latter being centered with respect to the casing 14 of the nozzle in the manner hereafter described. The return pipe 11 is also supported near the rear end of the inner casing in some suitable manner, as for example by set screws 15 engaging an outlet fitting 16 which is threaded on the pipe 11 and which is tightly clamped on the inner oil duct 10 by a nipple 24. This fitting 16 has a lateral outlet 17 affording a connection to the rear end of a coiled pipe 18, which coiled pipe is desirably made of copper and is recurved at its forward end so as to provide a return portion 19 extending within the coil for the greater portion of the length of the latter.

The casing 14 of the nozzle is desirably screwed upon the forward end of the inner casing or steam chamber 2 and has a mouth 30 of somewhat larger diameter than the forward end of the nozzle core 13 so as to leave an annular space for the emission of the fluid from the nozzle, the forward ends of both the nozzle core and the nozzle casing being tapered so that this space can be varied in width by moving the core longitudinally of the casing.

In operating the nozzle as thus described, oil under suitable pressure is admitted from the oil supply pipe 8 through the bore of the elbow 9 into the forwardly extending and axially mounted oil duct 10 through which the oil flows almost to the nozzle core. Then the oil returns along the outside of this duct 10, or between the latter and the bore of the larger return pipe 11, flows through the outlet 17 and the coil 18 and then back through the return pipe portion 19. Meanwhile, steam under pressure is admitted from the steam supply pipe 7 into the bore of the elbow 6 and flows through the inner casing 2 and out through the space between the nozzle core 13 and the nozzle casing 14. In doing so, this steam is mixed with the oil issuing from the rearwardly directed outlet of the oil pipe 19, but this mixing is only effected after the oil has flown back and forth through the inner casing several times. Owing to this repeated passage of the oil through the casing which is otherwise filled with the live steam, the oil is highly preheated, and particularly so owing to the length of the portion of the oil duct which forms the coil 18 and the fact that this

coil has all its surface portions exposed to the steam. Consequently, the oil is substantially vaporized by the time it leaves the return pipe 19, so that it will readily mix to a highly effective degree with the steam and will issue in the form of an intimate mixture from the nozzle of the burner.

As a further means of increasing the thoroughness of this mixing and for the additional purpose of keeping the resulting flame within a reasonable distance from the mouth of the nozzle, I desirably also provide flame spreading at the mouth of the nozzle. For this purpose, I am here showing the nozzle core 13 as having a plug 20 threaded into its forward end. This plug 20 carries an axle 21 extending coaxially with the nozzle core and this axle has rotatably mounted on it a movable member comprising a series of fan blades 22 all of which have rear faces oblique to the general direction in which the fluid issues from the nozzle. These blades 22 project beyond the mouth of the nozzle radially of the axle 21, so that they are continually in the path of the issuing fluid and the pressure of this fluid will therefore cause the fan-shaped rotating member to revolve. In doing so, it increases the thorough intermingling of the steam with the oil and also spreads the mixture axially of the nozzle so as to impart a corresponding spread to the flame instead of having the latter projected in the form of a relatively long and pointed jet.

At the same time, the flow of the fluid through the nozzle produces a suction around the exterior of the nozzle casing and hence causes air to flow through the passage 5 between the inner and outer casings, thereby supplying the air needed for the combustion. As this air flows along the outer surface of the inner casing through which the steam is flowing, the air is also preheated, thereby increasing the efficiency of the burner. By loosening the set screws 3 and 4, I can readily shift the position of all of the other parts with respect to the outer casing 1, thus increasing or decreasing the distance between the forward end of the outer casing 1 and the rear end of the nozzle, so as to control the amount of the air supply. So also, by first loosening the set screws 7 and 15, I can shift the position of the nozzle core and the parts connected to the latter with respect to the nozzle casing, so as to control the flow of steam through the nozzle and to vary the spread of the hollow cone in which the nozzle proper tends to project the issued fluid. Furthermore, by having the various portions threadedly connected as here illustrated, I can readily take any desired portions apart for inspection or

cleaning if necessary, or even for replacing any parts which may wear out in time.

However, while I have illustrated and described my burner in a particular embodiment including certain desirable threaded connections, I do not wish to be limited to these or other details of the construction and arrangement here disclosed. Obviously these might be varied in many ways without departing either from the spirit of my invention or from the appended claims. Neither do I wish to be limited to the use of my rotating flame spreader and of the oil-preheating and mixing portions of my invention in connection with each other, although I have found the combination of the same as here presented to be highly effective and have also found that my arrangement affords a desirable preheating of the air while the latter is flowing through the passage 5.

I claim as my invention:—

1. An oil burner, a steam casing, an oil duct, a return oil pipe spaced from and surrounding the oil duct, a nozzle connected to the steam casing, and a coiled pipe connected to the inner end of the return pipe and surrounding the return pipe and having its opposite end extending inwardly and disposed between the coils of the coiled pipe and the return pipe so as to cause the oil to traverse the steam casing three times and to then effect discharge of the oil at a point intermediate the length of the coils of the coiled pipe.

2. An oil burner comprising a steam chamber having a forwardly directed outlet, an oil duct extending into the steam chamber and opening into the latter, and a nozzle core carried by the oil duct and disposed within the steam outlet to afford an annular nozzle mouth, the oil tube having a pair of portions housing one another to afford a return passage between the two portions.

3. An oil burner as per claim 2, in which the oil duct includes an inner portion extending forwardly into the steam chamber toward the nozzle core, an outer portion freely housing the inner portion and carrying the nozzle core, and an outlet fitting connecting the rear end of the outer portion with the inner portion so as to support the said rear end.

4. An oil burner as per claim 2, in which the oil duct includes an inner portion extending forwardly into the steam chamber toward the nozzle core, an outer portion freely housing the inner portion and carrying the nozzle core; in combination with an outlet fitting supporting the rear end of the outer portion concentric with the inner portion, and a coiled portion coiled around the said outer portion and supported by the outlet fitting.

5. In an oil burner, a steam casing, an oil duct in the casing, a two-part nozzle, the parts of which are carried by the casing and duct respectively, an outer air casing surrounding the steam casing in spaced relation thereto and having each of its ends open and having one end disposed adjacent to the outer part of the nozzle so as to cause the air to flow over the outer nozzle part, and two series of set screws projected through the air casing and impinged at their inner ends against the periphery of the steam casing.

6. In an oil burner, a steam casing, an oil duct in the casing, a two-part nozzle the parts of which are carried by the casing and duct respectively, an outer air casing surrounding the steam casing in spaced relation thereto and having each of its ends open and having one end disposed adjacent to the outer part of the nozzle so as to cause the air to flow over the outer nozzle part, and means to connect the air casing to the steam casing in its said spaced relation thereto.

7. An oil burner comprising a nozzle, a steam supply chamber connected to the nozzle for discharging through the latter, and an oil supply duct extending into the steam chamber and opening into the latter; the said duct comprising a forwardly extending pipe, a rearwardly extending pipe housing the aforesaid pipe, and a pipe coil housing portions of both of the aforesaid pipes.

8. In an oil burner, a steam casing, a nozzle at one end of the casing, means to supply fuel to the nozzle, an air casing surrounding the steam casing and having each of its ends open to the surrounding air and having one of its ends disposed adjacent to the nozzle, and means to support the air casing in spaced relation to the steam casing, said air casing extending substantially throughout the length of the steam casing, whereby the air will be effectively heated in its passage through said space.

9. In an oil burner, a steam casing, an oil pipe therein, a nozzle connected to an end of the steam casing and having an inner member, an oil return pipe spacedly surrounding the oil pipe and connected at its outer end to the inner nozzle member, a coiled pipe surrounding the return pipe, and means to connect the inner end of the coiled pipe to the inner end of the return pipe.

10. In an oil burner, a steam casing, a nozzle at one end of the casing, an oil feed pipe in the casing, an oil return pipe surrounding the feed pipe, and a coiled pipe surrounding the return pipe and connected to the latter at the inner end thereof whereby the oil is caused to travel the length of the steam casing three times before delivery to the nozzle.

11. In an oil burner, a steam casing, a noz-

zle at one end of the casing, means to convey oil from the other end of the casing and along the length of the casing and interiorly thereof, means to receive and then return the oil along the length of the steam casing toward the first named end thereof, and means connected to the return means to re-

convey the oil toward the nozzle, whereby the oil is caused to traverse the casing three times before delivery to the nozzle. ¹⁰

Signed at Chicago, Illinois, January 9th, 1923.

JOHN R. WATTS.
